Primary Examiner — John Windmuller*(74) Attorney, Agent, or Firm* — Richard J. Bartz**CLAIM**

The ornamental design for a combined mat and EAS antenna, as shown and described.

DESCRIPTION

FIG. 1 is a top plan view of the combined mat and EAS antenna of my new design;
 FIG. 2 is a front end elevation view thereof;
 FIG. 3 is a rear end elevational view thereof;
 FIG. 4 is a bottom plan view thereof;
 FIG. 5 is a right side elevational view thereof;
 FIG. 6 is a left side elevational view thereof;
 FIG. 7 is a sectional view taken along line 7-7 of FIG. 1;
 FIG. 8 is a sectional view taken along line 8-8 of FIG. 2; and,
 FIG. 9 is a sectional view taken along line 9-9 of FIG. 1.
 The broken lines in FIGS. 4 and 9 depict portions of the antenna that form no part of the claimed design.
